UNITED STATES PATENT OFFICE.

CHARLES G. MACGREGOR AND HENRY KLECKLER, OF BUFFALO, NEW YORK.

DESIGN FOR A HYDROAEROPLANE-PONTOON.

52,847.

Specification for Design.

Patented Jan. 7, 1919.

Application filed November 10, 1917. Serial No. 201,386. Term of patent 7 years.

To all whom it may concern:

Be it known that we, CHARLES G. MACGREGOR and HENRY KLECKLER, citizens of the United States residing at Buffalo, in the county of Erie and State of New York, have invented a new, original, and ornamental Design for a Hydroaeroplane-Pontoon, of which the following is a specification, reference being had to the accompanying drawings, forming part thereof.

Figure 1 is a top plan view of the pontoon, and

Fig. 2 is a side elevation.

We claim:

The ornamental design for a hydroaero-plane pontoon, substantially as shown.

CHARLES G. MACGREGOR.
HENRY KLECKLER.

Witnesses:

WM. E. EBALK, JR.,
CHAS. H. KEEL.
